UNITED STATES PATENT OFFICE.

EDWIN JOSEPH SMITH, OF LONDON, ENGLAND.

DOOR-BOLT.

1,345,031.

Specification of Letters Patent. Patented June 29, 1920.

Application filed September 4, 1919. Serial No. 321,676.

To all whom it may concern:

Be it known that I, EDWIN JOSEPH SMITH, a subject of the King of England, residing at London, England, have invented certain 5 Improvements in Door-Bolts, of which the following is a specification.

The present invention relates to a door bolt for use with double-doors instead of the customary flush or surface bolt, and consists in the provision in a lock casing of two 10 spring-supported bolts set at right angles and coupled together by a bell-crank lever, one bolt having a rounded end projecting normally but slightly from the casing, the other bolt being beveled and also projecting normally from the casing. The arrangement is such that the rounded bolt, which 15 normally only projects enough to retain the door in shut position, is shot when the beveled bolt is forced back into the casing by the shutting of the lock door.

In the accompanying drawing the invention is illustrated by a perspective view of the mechanism.

25 In a lock casing *a* are arranged two bolts *b* and *c* at right angles to each other. These bolts are coupled together by a bell-crank lever *d* turning about a pivot and causing one bolt to be shot when the other one is 30 retracted. The bolt *c* has a beveled end and is normally retained by a spring *e* in a projecting position. Another spring *f*, weaker than the spring *e*, supports the bolt *b* which has a rounded end projecting normally only 35 to the extent of the rounded portion from the casing *a*.

The casing is fitted in the edge of the door with the bolt *b* directed toward the door frame, which has a mortise for its reception, and projects only just enough to retain the door in shut position, yielding so that the door can be easily opened and shut. The bolt *c* is directed toward the door fitted with the lock. When the latter

door is shut, it strikes against the bolt *c* 45 and forces it back into the casing *a*, the result being to shoot the bolt *b* completely. The doors are thus fixed and locked by one single operation.

The bolt *c* is preferably made reversible 50 so that the same structure can be used either for the upper or lower corner of the door.

The bolt is suitable for all light double-doors employed in furniture, delivery vans 55 and the like.

I claim:—

1. A door bolt comprising a casing, two 60 spring-supported bolts arranged at right angles in said casing, one bolt having a rounded end, the rounded portion projecting normally from the casing, the other bolt being beveled, the beveled portion projecting normally from the casing, and a bell-crank lever arranged in the casing and engaging 65 the two bolts so as to cause the round-ended bolt to be shot completely when the beveled bolt is forced into the casing, substantially as and for the purpose set forth.

2. A door bolt comprising a casing, two 70 spring-supported bolts arranged at right angles in said casing, one bolt having a rounded end, the rounded portion projecting normally from the casing, the other bolt being beveled, the beveled portion projecting normally from the casing, and a bell-crank lever arranged in the casing and engaging 75 the two bolts so as to cause the round-ended bolt to be shot completely when the beveled bolt is forced into the cas- 80 ing, the beveled bolt being reversible so that the bevel can be turned to either side of the case, substantially as and for the purpose set forth.

EDWIN JOSEPH SMITH.
